UNITED STATES PATENT OFFICE.

BURT EUGENE TAYLOR, OF RANDOLPH, NEW YORK, ASSIGNOR TO BORDEN'S CONDENSED MILK COMPANY, OF NEW YORK, N. Y., A CORPORATION OF NEW JERSEY.

CAN-CAPPING MACHINE AND FEEDING DEVICE THERETO ADAPTED

1,029,326.

Specification of Letters Patent. Patented June 11, 1912.

Application filed October 5, 1909. Serial No. 521,125.

To all whom it may concern:

Be it known that I, BURT EUGENE TAYLOR, a citizen of the United States, and a resident of Randolph, in the county of Catskill and State of New York, have invented certain new and useful Improvements in Can-Capping Machines and Feeding Devices Thereto Adapted, of which the following is a specification.

10 My invention relates to that class of can capping machines usually applied to cylindrical cans, such as condensed milk cans, having a flanged opening in the top, on which opening, after the cans have been 15 filled with the milk, is placed a correspondingly flanged cap, which is forcibly depressed into said opening until said flanges contact, after which the said flange of the cap is crimped with the said flange of the 20 can to constitute an air-tight seam and exclusion of the contents from the atmosphere. The cans, in the operations referred to, are 25 propelled, uprightly supported, to the crimping mechanism, whereby loss of contents is avoided.

The objects of my invention are to provide more economical, efficient, and labor-saving devices than heretofore used, whereby the filled cans are, automatically, fed to 30 the points of operation, their caps forced down to place, the cans centered by centering fingers, the crimped can removed from the crimping mechanism, the top of the can printed with the desired designation, and 35 a plurality of said cans automatically, intermittently, propelled in sequence through, and operated on, as described, in a single organized machine.

The aforesaid objects I attain by means 40 of the instrumentalities, devices, and combinations of devices hereinafter described and illustrated in the accompanying drawings, in which—

Figure 1 is a side elevation of parts of my 45 machine, seen in the direction of arrow $a-a$, on section $a-a$ of Fig. 2; Fig. 2 is a plan on line $b-b$ of Fig. 1, certain parts being omitted; Fig. 3 is a front elevation, seen from the left of Fig. 1, showing operating 50 mechanisms for movable elements of my machine, the upper part of the crimping mechanism being broken away; Fig. 4 is a fragmentary vertical section, on line $c-c$ of Fig.

2, seen in direction of arrow c ; Fig. 5 is an enlarged plan detail view showing my centering fingers; Fig. 6 is an enlarged plan detail of my improved chuck; Fig. 7 is a side elevation of Fig. 6; Fig. 8 is a side elevation of Fig. 6, partly in section on line $d-d$ of Fig. 6 and showing part of a can; Fig. 9 is a similar view, the section being taken on line $e-e$ of Fig. 6 and in part of the can; Fig. 10 is an enlarged detail side elevation of the chuck, showing my device for locking latter; Fig. 11 is an enlarged detail side elevation of my printing device, and some of its actuating parts; Fig. 12 is a diagrammatic view of the chuck and crimper operating cams, showing their relative timing; Figs. 13 to 16 are diagrammatic views illustrating consecutive steps in crimping the caps to the cans; Figs. 17 and 18 are diagrammatic views showing different positions of my cap presser-foot canis during operation; Fig. 19 is a diagrammatic view on enlarged scale of disks carrying pins whereby a step by step rotation is imparted from main shaft to the sprocket wheel actuating the endless chain carrying flights which advance the cans intermittently; Fig. 20 is a diagrammatic view on enlarged scale of disk, on main shaft, provided with pins which actuate the lever by which the crimping mechanism is turned on; Fig. 21 is a diagrammatic view on enlarged scale of the cam, on main shaft, which actuates the cap presser-foot; Fig. 22 is a diagrammatic view of enlarged scale illustrating the timing of the cap presser-foot-operating cam relatively to the cam which actuates the lower chuck of the crimping device; Fig. 23 is a sectional detail view, on enlarged scale, of my clutch controlling portion of the crimping mechanism; Fig. 24 is a top plan view, on enlarged scale, of the head which controls said clutch; Fig. 25 is an enlarged rear elevation of mechanism controlling operation of said clutch and my cam feeding devices. Similar reference numerals refer to similar parts throughout the several views.

It will be understood that the crimping mechanism illustrated constitutes no part of my invention, except as hereinafter claimed in combination, but inasmuch as the construction, operation and effect of the crimp-

ing mechanism are affected by my present improvements, and they in turn thereby, it has appeared necessary to illustrate, and describe, as I have done, one well known type 5 of such crimping mechanism, to the end that my said improvements, and organized machine containing them, may be fully understood.

Referring to Fig. 1, a crimping mechanism is indicated by 1, the same comprising a base 2, to which an upper frame 3 is secured. Frame 3, adjacent the front thereof, is provided with a rotatable spindle 4, carrying at its lower end a thereto relatively rotatable chuck 5, against which the caps of the cans are held by another vertically movable chuck 6. 7 is a slidable sleeve, on spindle 4, having a conical cam 8, adapted to force the pivoted arms 9 and 10 outwardly 10 when sleeve 7 is depressed by lever-arm 11, actuated by cam 12. Chuck 6 is moved vertically by recess 13 in cam 14 (see Fig. 12) through medium of plunger-arm 15, lever-arm 16 and vertically movable rod 17, the 15 last above named elements being returned to normal position after each actuation by spring 18, cam 12 and cam 14 being shown in such position in Fig. 12. Cam 12 and cam 14 are mounted on shaft 19, carrying 20 disk 20, carrying a slidable spring-actuated pin 21 (Fig. 23). Adjacent disk 20, on shaft 19, is gear 22, having recesses 23 therein adapted to be engaged by pin 21. Gear 22 is rotated by a pinion 23^a, which is, in 25 turn, actuated by beveled gears 24 and 25, through belt 26 on pulley 27. Adjacent pulley 27 is a loose pulley 28 for the usual purpose. Spindle 4 is rotated through pulleys 29 and 30, connected by a belt 31. Spindle 4, adjacent chuck 5, has secured thereto bracket 32, to which said arms 9 and 10 are pivotally secured. These arms are each provided with a rotary crimpler 33 and 34 respectively. Crimpler 33 has a broader face 35 than crimpler 33. The angle of the periphery, or working face, of crimpler 34 is greater than that of crimpler 33. Arm 9 is longer than arm 10. It follows that 33 begins the crimping operation and 34 completes it. As 40 sleeve 7 descends, cam 8 will first contact with friction-roller 9' on arm 9, and push latter outwardly, thereby causing 33 to contact flange of the can cap and turn it down and inwardly to an extent. Continued descent of cam 8 forces it against roller 10' on arm 10, moving latter outwardly, whereby 34 is, in turn, forced against the now partly crimped flange of said cap, and, owing to the greater pitch of its periphery, forces said 45 flange firmly against the flange 40 of the can. Figs. 15 and 16 illustrate the said operation. 33 and 34 rotate while performing their said function. It will be observed that the foregoing construction implies a pair of 50 chucks relatively movable toward and from

each other on a common axis, a crimping device rotatable relatively thereto in paths concentric with said axis, and means to so move said chucks and crimping device relatively to each other. The foregoing describes one form of crimping mechanism adapted to be utilized with, and subserve the action of, my said improvements, which I will now more particularly describe.

The cans, for instance of the cylindrical form shown in the drawings (Figs. 15 and 16), having been filled as usual through the openings 39 in their tops with the desired contents, as for instance condensed milk, are moved, one by one, from under the nozzle of the pump utilized to accomplish said filling by a horizontally rotatable circular carrier, a portion of which is indicated by 35 (Fig. 2), comprising peripherally disposed recesses 36, opening outwardly and each adapted to receive a can 37. My said carrier is horizontally rotated, step by step, in direction of arrow 38, the empty cans being fed to the recess 36 in advance of the pump nozzle, not shown, by any suitable means. It will be understood that the cans 37 shown in the drawings (Fig. 2, etc.), have all received their quota of contents, e. g., condensed milk, and the can flange, hereinbefore referred to, is, in the drawings, indicated by the designation 40. As carrier 35 is intermittently rotated, the filled cans are, one by one, introduced into my improved race-way, the floor of which is, in part, constituted by the surface of the table 55, and the sides by stationary, laterally disposed, guiding members, as for instance rails 41 and 42.

It will be observed, on reference to Fig. 2, that the ends of the rails adjacent the entrance of the race-way are curved as shown. The said curved portions co-act on the cans, as introduced into said entrance by rotation of the carrier 35, to force the cans out of the said recesses in said carrier. Another part of the floor of my said race-way is constituted by an endless belt 43 (Figs. 2 and 4). Belt 43 is propelled in the direction in which the cans are pushed by the carrier 35 as follows:—On main-shaft of the machine 45, is secured a beveled gear 44, which meshes with beveled idler gear 44^a, loosely rotatably mounted on shaft 44^b, rigidly secured to horizontal cross-bar 48. Beveled gear 44^a intermeshes in turn with beveled gear 44^c, secured to sleeve 44^d on main driving shaft 45, journaled in bearings 46, mounted in dependent supports 47, secured to horizontal bars 48, which are, in turn, secured to base 2 of the machine. Belt 43 passes over sleeve 44^d by which it is actuated, and over idler pulleys 49, 50 and 51, carried in bearings 53 and 54 (Fig. 3) under table 55. By this means propulsion in the desired direction is imparted to belt 43 through agency of main-shaft.

Adjustability of upper surface of chuck 6, relatively to upper surface of table 55, I secure by mounting latter on vertically adjustable slats, or supports, 57 (Fig. 3), said slats being movably secured to bars 48 as shown. Upper surface of belt 43 should be as nearly flush as possible with upper surface of table 55, as shown in Fig. 4. 58 indicates additional guiding members, in continuation of rails 41, 42, to keep the cans in alinement.

I provide, adjacent the discharge end of belt 43, an endless can conveyer, in this instance comprising an endless sprocket-chain 61, longitudinally disposed, as shown, at right angles to said belt. Said chain carries a plurality of flights 60, spaced to form, between them, pockets 59, each adapted to receive and loosely hold a can. 62 and 63 are sprocket-wheels, adapted to engage with said sprocket-chain, 62 being, in this instance, an actuating, and 63 an idler, wheel. Chain 61 is of the well known interlocking link variety, the flights 60 being thereto secured in the usual manner of the link belt art. Sprocket-wheel 63 is mounted in bearings 64, adapted for longitudinal movement on bars 48 to permit tautening of chain 61 as desired. Actuating driving sprocket 62 is carried by rotatable counter-shaft 65, mounted in bearings 66, on bars 48 (Fig. 3). 65 carries also a disk 67, having predeterminedly disposed projections, or pins, 68 (in this instance eight of them). To rotate shaft 65 is mounted on main-shaft 45 a disk 69, having also predeterminedly disposed projections, or pins, 70 (in this instance three of them). Main-shaft 45 is rotated by belt-pulley 71, a clutch 72 being employed to operatively connect said last mentioned pulley and shaft as required. Said disks 67 and 69, and their respective projections, or pins, are so proportioned, disposed and timed, relatively to each other, as to cause shaft 65 to rotate sufficiently to advance sprocket-chain 61 the distance between the centers of two adjacent cans, as held between the flights 60, each time one of pins 70 engages with and advances a pin 68. Therefore, in the construction illustrated, . . . a 61 is advanced three steps during each revolution of main-shaft 45. Fig. 19 illustrates relative movements of said pins, dotted lines showing a pin 70 approaching engagement with pin 68, and full lines same pin 70 about to leave pin 68.

The devices are so disposed, proportioned and timed that each step of chain 61 feeds a can under chuck 5 of the crimping mechanism and over chuck 6 into approximately the position shown in Fig. 1. During each one-third rotation of disk 69, a cycle of the crimping operations occurs. While chain 61 is intermittently at rest, a can will be

propelled by belt 43 into a therewith alined recess 59, between the flights 60 of the can feeding mechanism. Before said can enters said recess, an operator manually places a cap 72 over opening 39 of the can. Fig. 13 illustrates how said cap is thereby disposed. Said cap must, before the crimping mechanism is reached, be forced home into said opening, an operation which one of my improvements is designed to accomplish, as follows:—The aforesaid intermittent, step by step, advance of chain 61, brings the cans, one by one, under my cap presser-foot 73, which is normally supported above the path of said feeding mechanism, anterior the said crimping mechanism. I provide means to intermittently depress and raise said presser-foot while the can remains thereunder, during each intermission in the advance of said cans, thereby insuring the forcing of the caps into the aforesaid required position (Fig. 14). Said means are as follows:—Presser-foot 73 is normally supported above the path of feed of the cans sufficiently to admit free passage there-of thereunder, it being so upheld by a concentric portion 76 (Fig. 21) of a cam disk 77 on main shaft 45 (Fig. 3), on which rides a roller 77', connected with the rod 80, slidably supported in guideways 80', secured to the bar 48, said presser-foot 73 being secured to the upper end of said rod 80. A retractile spring 79 is secured to said rod and to a stationary part, i. e. one of the bars 48. When a can, by my aforesaid intermittent feed, has been fed to, and left momentarily stationary in, a position under said presser-foot, a recess 78 in disk 77 will, by rotation of main-shaft 45, have been brought to position relatively to said roller, as indicated in Fig. 17, whereby spring 79 (Fig. 3) will pull down rod 80, and its thereby carried presser-foot, to force the cap home as aforesaid, and continued rotation of disk 77 will thereafter again raise said presser-foot to normal position above the pathway of the feeding mechanism. Under presser-foot 73, part of the otherwise solid surface of the floor of the can runway, i. e. table 55, is cut away, to provide an opening 74 in said floor passable by a cap. Said opening, in the instance illustrated in the drawings, is shown provided with a grating of bars 74', spaced to provide between them openings likewise passable by a cap, the object of this device being to provide an escape for caps accidentally dislodged, and thus remove them from interfering with free passage of the cans.

I provide means for insuring the release of the cans from the crimping mechanism as follows:—Adjacent to one side of the aforesaid crimping mechanism I provide a support 83'. On said support is pivoted a lever 83, having its free end normally dis-

posed adjacent said chuck 5, and above the path of said feeding mechanism, and its opposite end disposed to be raised by said rod 80 through the medium of another vertically movable rod or plunger 82 (Fig. 1) connected with rod 80 by cross-arm 81. A retractile spring 83² is connected with said lever 83 and a stationary part to maintain the free operative end of said lever in normal position above the path of feed when not depressed by upward movement of rod 82 acting against the tension of spring 83². The said free working end of lever 83 is preferably of bifurcated conformation, as shown in Fig. 2, thus presenting two fingers 84¹, 84², one on each side of said can releasing device, or straddling the line of concentric alinement between chucks 5 and 6, whereby, when the lever is depressed as aforesaid, is insured a positive and substantially equal pressure downward simultaneously on two opposite sides of the can top, whereby its release in proper position from the crimping mechanism, to which it often undesirably adheres, is insured. The can-releasing lever 83 and its bifurcated head 84¹, 84², is depressed intermittently, as will be obvious, by the same before described cam action which actuates the rod 80, the end 87 of said lever 83 being thereby forced upwardly by rod 82 (Fig. 1), whereby its bifurcated jaw is caused to strike the can and force it down and off of chuck 5. When rod 80 slides down again, on continued rotation of cam-disk 77, spring 83² returns lever 83 to its said normal position, by pulling down its said end 87. Said release of the can takes place just before chain 61 is advanced another step to bring the following can between chuck 5 and chuck 6 and still another can to its required position under presser-foot 73.

I provide means to positively adjust the cans into position concentric with said common axis on which chucks 5 and 6 are movable relatively to each other, *i. e.* to exactly center them in the crimping mechanism, which is of great importance and advantage in this art. To this end I employ a plurality of oppositely disposed and bearing spring-tensioned fingers, 88, 89, having their free operative ends held normally to a circle concentric with said axis and coinciding with the cylindrical circumference of the can (Fig. 5). Said fingers 88, 89, on the right hand of the path of the feeding mechanism, as seen in Fig. 2, are pivotally connected to guard rail 90, secured to table 55 as at 90^a, said rail functioning, as aforesaid, to retain the cans in the pockets 59. The fingers 88 and 89 on the left hand of said pathway of the feeding device, as shown in Fig. 5, are pivoted to foot 91 of guide rail 92 as at 93. Guide rail 92 is provided with groove 93^a (Fig. 4) through which chain

61 passes. The said fingers are connected by retractile springs 88', 89', with the adjustable blocks 95 (Figs. 2 and 5) provided to adjust the gripping or operative ends 94 of said fingers relatively to circumference of the cans. The free ends 94 of said fingers being, as aforesaid, oppositely and concentrically disposed relatively to the said common axis of chucks 5 and 6, it follows that the cans and their then positioned caps will, by pressure of said fingers under tension, be positively and accurately centered concentrically with the aforesaid common axis of chucks, and crimpers, which is of great importance and advantage. As the cans are moved or fed toward and from their said concentricity with said axis, *i. e.* to center with said chucks, they will encounter and bear against the free or operative ends of said fingers, which stand movably tensioned in said path of the feeding mechanism and its thereby propelled cans. At this stage the fingers yield to allow passage of the can between them. After such passage has been accomplished, the fingers are retracted by their said springs toward normal position, thereby positively pushing the can to required center. Thus, in the construction above shown, the can having parted, and passed through, the first pair of fingers, is brought, approximately simultaneously with a pause in the feeding mechanism, into abutting contact with the operative ends of the second pair of fingers, whereupon the first pair are, by their springs, forced back into abutting contact with the can, and, coöperating with the second pair of fingers, adjust the can to the exact position required, which is attained when the opposite ends of said fingers bring up against their respective stop-blocks 95. After the cap has been crimped, the now "sealed" can will, by the next advance of the sprocket-chain 61, be similarly forced between, and through, the second pair of fingers 88, whence it is finally pushed onto an ordinary conveyer belt 97, whereby it is removed to where desired.

I provide means to check the rotation of the can on its axis while subjected to the pressure and movement of the rotatory crimping mechanism. To this end I provide the chuck 6 with a plurality of raised portions, or gripping blades, 98 (Figs. 6 to 9), having their operative edges disposed upwardly and extending radially from said chuck's center of alinement with chuck 5 and the crimpers. Said blades are so positioned in the chuck 6 as to engage against the edge 99 in the bottom of the can (Fig. 125 9). The blades 98 are preferably not provided with an actual cutting edge, but are edged just sufficiently to enable them to exert strong friction without cutting the can, and thereby prevent latter from rotat- 130

ing while the crimpers are at work. Chuck 6 is also provided with a plurality of removable oppositely disposed members or blocks 100, having inwardly inclined faces, disposed concentrically with said chuck 6 and its aforesaid concentric alinement with chuck 5 and other members of the crimping device (Figs. 6 and 8). The blocks 100 thus aid to preliminarily approximately 10 center the cans, and the fingers 88, 89, finally bring them into exact position as aforesaid. The blocks 100 are preferably adapted to be interchanged for others of different dimensions to suit different sizes of cans.

15 I provide means to prevent chuck 6 from chattering and enable it to resist rotatory impulses thereto communicated through the can from strains exerted on latter by the crimpers. To this end I provide said chuck 20 with transverse slots 102 (Figs. 6, 7, 8, 9, 10). Bars 101 rigidly secured to a stationary part of the machine, as for instance to the table 55 as shown in Fig. 6, are disposed to extend slidably, at all times, through said 25 slots in the path of the upward and downward movements of chuck 6. Said bars therefore prevent chucks 6 from rotating without impeding its vertical reciprocation.

30 I accomplish the actuation or "turning on" of the crimping mechanism, when required, as follows:—When the feeding mechanism, comprising the sprocket-chain 61, is operated as aforesaid by rotation of main-shaft 45, there is, thereby, imparted 35 rotation to disk 105 (Figs. 1 and 3) secured to said main-shaft. Said disk 105 is provided with predeterminedly disposed projections, or pins, 104. A lever 103 is pivoted to a stationary part, and is disposed 40 with its free end normally in the path of said last mentioned projections. 106 is a vertically movable bar, having its lower end connected with said lever, and its upper end provided with a head 107 (Fig. 24) having 45 a curved portion 108 disposed normally in the path of a heel 109 on the hereinbefore referred to pin 21 (Fig. 23). Said head 107 of bar 106 is kept normally in contact with said heel 109 of pin 21 by the retractile 50 spring 110 (Fig. 1) connected with said lever 103 and with a stationary part, and disposed to return said lever and bar 106 to normal position. While the head 107 is in its uppermost position, the spindle 4 55 and other therewith connected operating elements of the crimping mechanism will remain at rest. When, however, the lever 103 is depressed by pressure thereon from one 60 of the pins 104, head 107 will be moved away from heel 109 of pin 21, whereby a leaf-spring 111 (Figs. 23 and 25) forces pin 21 toward a recess 23 in gear 22, which said pin thereupon enters, and whereby gear 22, which, as aforesaid, is constantly rotating, 65 is operatively connected with disk 20, and

motion thereby communicated to the crimping mechanism, and shaft 19 will make one revolution, but no more, because as soon as pin 104 leaves the end of lever 103, said spring 110 causes head 107 to rise again into 70 its normal position in the path of heel 109. When said heel, in the course of its rotation, strikes again the curved end of head 107, it is forced inwardly, thereby withdrawing pin 21 from the recess 23 in gear 22. 75

To control the operation of the crimping mechanism and can feeding mechanism, I provide a lever 112 (Figs. 3 and 25), the lower end of which operates a clutch 72. Intermediate the ends of lever 112, and 80 above its pivotal point 113, (Fig. 25), I pivotally secure thereto one end of a link 114, and the opposite end of said link also pivotally to a rocking-arm 115, the upper end of which engages a pin 116 on bar 106. It 85 is obvious that while said arm is in engagement with said pin, the mechanisms cannot operate. By moving upper end of lever 112 to the right (Fig. 25) clutch 72 is thrown in, bar 106 released, and operative connection 90 established between the constantly running pulley 71 and main-shaft 45 of the machine.

I provide means for printing automatically the top of the cans, after they have left the crimping mechanism, as follows:—A 95 bracket 120 (Figs. 2 and 3) is supported and disposed, adjacent to, and one side of, the path of said feeding mechanism. Pivoted to said bracket is a lever-arm 119, having its free end normally disposed behind the crimping mechanism and above the path of the feeding mechanism, and its opposite end connected with an extension of the shaft 83³, journaled in support 83¹, carrying can-releasing lever 83, whereby latter is pivoted 100 to said support. The aforesaid connection between shaft 83³ and lever 119 is effected by means of arm 83⁴ on said last mentioned shaft, which arm carries a pin 122 engaging in jaw 119' in lever 119, from which construction it follows that when rod 80 is raised by cam disk 77, rear end of lever 83 is raised by rod 82, connected with rod 80 by arm 81, thereby imparting rotation to shaft 83³ and thus to arm 83⁴, whereby rear end of 115 lever 119 is caused to rise and its operative end pressed down to bring its thereby carried type into contact with the can top for printing latter. The type 117 is carried by a dovetailed block 118 held in correspondingly shaped recess in lever 119 by pressure of a set screw indicated by dotted lines (Fig. 11) thus providing for interchange of like blocks carrying different types. The type 117 is inked by a pad 123, carried by the 120 lever arm 124, said arm being linked to bracket 120 as shown (Fig. 11), whereby the pad is carried away from the type whenever lever 119 is, as aforesaid, depressed.

Some mechanical details, which are clearly 130

illustrated in the drawings, are not expressly referred to in this specification.

From the foregoing it follows that my hereinbefore described machine and improvements operate substantially simultaneously on a plurality of cans, which are members of a group, manipulated as a whole, the operation being summarized as follows:—The carrier 35 feeds the cans, one by one, in a continuously consecutive procession into the raceway, where their propulsion is continued by the belt 43, which feeds them, one by one, into adjoining recesses between the flights carried by the sprocket-chain, traveling at right angles to said belt. The feed is step by step, or intermittent, and is actuated, and interrupted, by the same main-shaft, which, during the periods of interruption, actuates substantially simultaneously the three operations on three members of the entire group of cans under treatment, to wit, 1, the down-forcing of the cap into position, 2, the removal of the can from the crimping mechanism after crimping, and, 3, the printing, and which main-shaft also automatically turns on the crimping mechanism, the same main-shaft also simultaneously supplying the power which propels the cans into the recesses between the flights of the sprocket-chain conveyer, and also, intermittently, the power required for the operation of the fingers which center the can in concentric alinement with the chuck and crimping mechanisms.

It will be appreciated that my above described improvements are usefully applicable not only to cans specifically but also to any other cylindrical containers, including for instance bottles, which it is desired, in path of feed, to center accurately relatively to any thereon operating device and for any purpose. Therefore I do not wish to be understood as confining myself to cans only or to the crimping of caps thereon.

What I claim as new and desire to secure by Letters Patent is the following, viz:—

1. The combination, with means to loosely hold, and feed in a horizontal path, toward a predetermined vertical axis a cylindrical container, of four oppositely-bearing independently horizontally movable spring-tensioned fingers having their operative ends normally projecting into said path and yieldingly held on a circle concentric with said axis and coinciding with the cylindrical circumference of said container.
2. The combination, with means to feed a cylindrical container to a position centering with a predetermined axis, of a pair of oppositely disposed spring-tensioned fingers having their operative ends disposed in the path of said feed and movably supported to positively impel said container toward said position, and another pair of oppositely disposed spring-tensioned fingers having their

operative ends likewise disposed in said path and movably supported to hold said container at said position against impulsion thereto imparted by said first mentioned pair of fingers.

3. The combination, with means to feed a cylindrical container to a position centering with a predetermined axis, of a pair of oppositely disposed spring-tensioned fingers having their operative ends disposed in the path of said feed and movably supported to positively impel said container toward said position, another pair of oppositely disposed spring-tensioned fingers having their ends likewise disposed in said path and movably supported to hold said container at said position against impulsion thereto imparted by said first mentioned pair of fingers, and means to hold, against their said spring impulsion, the operative ends of all said fingers normally in said path and on a predetermined circle concentric with said axis and coinciding with the cylindrical circumference of said container.

4. In a can-capping machine a crimping mechanism comprising a pair of chucks relatively movable on a common axis, a crimping device rotatable relatively thereto in paths concentric with said axis, and means to so move said chucks and crimping device, a shaft, means to rotate it, a cam on said shaft, a roller riding on said cam, a slidably supported rod connected with said roller, a can feeding mechanism, means to actuate intermittently said can-feeding mechanism whereby a can is fed to, left between, and advanced from between said chucks, a support adjacent one side of said crimping mechanism, pivoted to said support a lever having its free end normally disposed adjacent to said chucks and above the path of said feeding mechanism, and its opposite end disposed to be raised by said rod, a spring connecting said rod with a stationary part, and a spring connected with said lever to maintain it in its said normal position.

5. In a can-capping machine a crimping mechanism comprising a pair of chucks relatively movable on a common axis, a crimping device rotatable relatively thereto in paths concentric with said axis, and means to so move said chucks and crimping device, in combination with a can-feeding mechanism, means to actuate intermittently said feeding mechanism whereby a plurality of cans are intermittently advanced in sequence toward and from said crimping mechanism, a bifurcated movable can-releasing member normally supported above the path of said feeding mechanism adjacent said chucks its bifurcation straddling said axis, and means to intermittently depress and raise said member during each intermission in the advance of said cans,

whereby they are positively forced away from said crimping device and one of said chucks.

6. In a can-capping machine a crimping mechanism comprising a pair of chucks relatively movable on a common axis, a crimping device rotatable relatively thereto in paths concentric with said axis, and means to so move said chucks and crimping device, 10 a shaft, means to rotate it, a cam on said shaft, a roller riding on said cam, a slidably supported rod connected with said roller, a can feeding mechanism, means to actuate intermittently said can-feeding mechanism 15 whereby a can is fed to, left between, and advanced from between said chucks, a support adjacent one side of said crimping mechanism, pivoted to said support a lever having a bifurcated free end normally disposed adjacent to said chucks and above the 20 path of said feeding mechanism, and its opposite end disposed to be raised by said rod, a spring connecting said rod with a stationary part, and a spring connected with said 25 lever to maintain it in its said normal position.

7. In a machine for the purpose set forth, the combination of a horizontally disposed main-shaft; a can-runway projecting in part 30 allelism with and at a higher level than said main-shaft; a can-propelling mechanism comprising an endless sequence of flights; means operatively connected with said main-shaft to advance said flights intermittently 35 in the path of said runway; movably supported by a stationary part adjacent said runway a presser-foot having its operative end above said runway; means operatively connected with said main-shaft to depress 40 said operative end of said presser-foot during each pause in said advance of said flights; behind said presser-foot, supported adjacent to and in the path of said runway, a crimping device and a can-centering device; means to normally actuate said crimping device, means to intercept such actuation, means operatively connected with 45 said main-shaft to terminate such interception at the beginning of each pause in said advance of said flights, movably supported by a stationary part adjacent said crimping mechanism a can releasing member having its operative end above said runway, means operatively connected with said main-shaft to depress said operative end of said can releasing member after each said interception of actuation of said crimping device

and during each pause in the advance of said cans, whereby, during rotation of said main-shaft, a plurality of cans in procession 60 is simultaneously fed through the machine, each of said cans caused to pause in turn in operative relation to said presser-foot, said crimping device, and said cap-releasing member, and a plurality of said cans operated upon thereby during each said pause.

8. In a can-capping machine, a crimping mechanism comprising a pair of chucks relatively movable on a common axis, means to so move said chucks, means to intermittently feed a can between said chucks, a stationary support adjacent one side of said crimping mechanism, pivoted to said support a lever having a free operative end disposed adjacent to said chucks, a spring connecting a stationary part with said lever and tensioned to normally maintain its said operative end above the path of the can feed as aforesaid, a main shaft, and means operatively connected therewith to intermittently depress against the stress of said spring said free end of said lever whereby said can may be positively forced from one of said chucks.

9. In a can-capping machine a crimping mechanism comprising a vertically movable chuck and a pathway for a can thereunder, a stationary support adjacent one side of said crimping mechanism, pivoted to said support a lever having a free operative end disposed adjacent to said chuck, means to normally maintain said end above said pathway, a main shaft, and means operatively connected therewith to intermittently depress said end whereby said can may be positively forced away from said chuck.

10. The combination, with means to loosely hold, and feed in a horizontal path, toward a predetermined vertical axis, a cylindrical container, of a plurality of oppositely-bearing, independently, horizontally, movable pivoted fingers, springs disposed to yieldingly hold the operative ends of said fingers in said path, and adjustable blocks disposed to positively hold said ends against the stress of said springs on a predetermined circle concentric with said axis and coinciding with the cylindrical circumference of said container.
